UNITED STATES PATENT OFFICE.

KARL SENN, OF ALAMEDA, CALIFORNIA.

COMBINED BATEA, JIG, AND PAN MOTION CONCENTRATOR.

1,141,419.

Specification of Letters Patent.

Patented June 1, 1915.

Application filed June 18, 1914. Serial No. 845,841.

To all whom it may concern:

Be it known that I, KARL SENN, a citizen of the United States, residing at Alameda, in the county of Alameda and State of California, have invented new and useful Improvements in Combined Batea, Jig, and Pan Motion Concentrators, of which the following is a specification.

This invention relates to concentrating apparatus.

It is an object of this invention to provide means for subjecting ore pulp to a wave-producing motion, the waves acting concurrently with a current flow to carry off gangue, and to separate the values, both free and combined, from the pulp.

A particular object of the invention is to provide an apparatus for handling finely comminuted pulp or "slimes."

The invention consists of the parts and the construction and combination of parts as hereinafter more fully described and claimed, having reference to the accompanying drawings, in which—

Figure 1 is plan view. Fig. 2 is a side elevation partly in section. Fig. 3 is a detail sectional view. Fig. 4 is a detail section of the supporting column.

2 is a shallow, circular, concave pan erected upon a spider frame 3 attached to parallel beams 4. The beams 4 are supported upon upright spring legs 5 secured in pairs upon opposite sides of a carrier frame 6. The carrier is suspended for transverse or side shake by suspending arms 7, connected at their upper ends to standards 8. Journaled in the standards, at one side of the carrier 6, is a shaft 9, carrying eccentrics 10—10 with connecting rods 11 jointed to the carrier 6 for reciprocating the latter sidewise. The shaft 9 also carries an eccentric 12, connected by a link 13 to a rock lever 14 on a rock-shaft 15, journaled upon the carrier 6. The rock-shaft is connected by a rocker-arm or arms 16 to the pan beams 4 and reciprocates this perpendicularly to the carrier motion. The pan is, therefore, moved orbitally at every point by the combined fore and aft and side shakes.

Mounted above the center of the pan 2 is a feed head 17, having a valve plate 18, between the circumferential edge of which and the annular lip 19 of the head is formed a mouth 20. Below the head 17, and centrally of the pan 2, is a preliminary or initial bowl or batea 21, the ridge 22 of which

is higher than the mouth 20 of the head. The batea is supported upon screws 23 in the pan 2 and has a downwardly and outwardly turned flange 24 forming an annular aperture 25 above the adjacent surface of the pan and below the ridge of the pan 2. The height of the aperture may be varied by raising or lowering the batea 21. The center of the batea is deepened, with a side wall 26 of greater angle than the angle of the outer slope, and is provided with a removable screen bottom 27, of desired character, upon which is deposited a mobile mass, as a quantity of rounded bodies or steel balls 28.

At the bottom of the pan 2 is an open mouth cone 29, to the lower and small end of which is connected a discharge pipe 30. Connected to the cone, by a pipe 31, is a pump 32, the piston of which is connected to a convenient part of the carrier as shown in Fig. 2 so that the latter is used to drive the pump piston, the cylinder of which moves with the pan relative to the carrier 6. Suitable check-valves and cocks are provided, as at 33 and 34, to control the fluid flow.

The operation and function of the apparatus are as follows: Power from any suitable source being applied to the shaft 9, the carrier is reciprocated laterally carrying with it the pan. This latter is reciprocated at right angles to the carrier motion and, therefore, has an orbital gyration in a horizontal plane. Pulp is fed to the head 17 and discharged by the annular mouth 20 thereof onto the batea 21, which is filled with water which covers the mouth. The pulp issuing from the mouth 20 is immediately greatly diluted by the water in the batea and the heaviest values gravitate at once to the central bottom portion and enter the interstices in the mobile mass or between the balls 28, the largest particles being retained upon the screen 27 and the smaller passing through. Interposed between the screen 27 and the mouth of the cone 29 is a second screen 35 supporting a mobile mass, as balls 36. The concentrates accruing upon the screens 27—35 are constantly subjected, in addition to the agitating motion of the pan, to a hydraulic jiggling action derived from the pulsations of water from the pump 32 through the pipe 31. This jiggling prevents the concentrates from "packing" as well as the mobile mass of balls on each screen, but the additional effect of the hy-

draulic jiggling is to thin the accumulation and allow the heavy concentrates to find quick egress through the screens to the cone bottom. Meanwhile, the fine slime is kept 5 in suspension and is washed outward from below the batea 21 through the mouth 25. The quantity of water injected into the cone by the pump is regulated by the valve 34. Pulp flowing over the batea 21 runs down 10 the rim 24, the solids falling from its edge across the mouth. The suspended particles drift centrifugally while the lighter contents gravitate to the bottom of the pan and are washed outward by the wave action. 15 All of the pulp stratifying upon the pan is agitated by its gyrations and the concentrates or values move centripetally down the incline of the pan in opposition to the counter-current issuing from the mouth 25. To 20 add further clear water to the pulp and to control the outward counter-current at the mouth 25 without varying the pulsation from the pump, there is provided, below the batea, a circular pipe 37 perforated to 25 spray jets of water downwardly. This added quantity flows outwardly through the mouth 25 and the force of the counter-current acts to throw gangue outward while still permitting the concentrate to gravitate 30 toward the screen 35.

I have devised, constructed and successfully utilized an apparatus, as described, by which pulp is concentrated by gravitation, while subjected to agitation on a collecting 35 surface, is washed by counter-currents, and agitated by hydraulic jiggling.

Having thus described my invention, what I claim and desire to secure by Letters Patent is—

40 1. The combination in a concentrator, of a concave pan with a central discharge, means for feeding pulp at the center of the pan, a screen in the pan discharge and supporting a mobile mass, the particles of which 45 are too large to pass through the screen, means for gyrating the pan to agitate said mass and the ore solids concentrated, the concentrate gravitating toward and through the screen and the gangue being washed outwardly by the wave action and water flow, means for 50 hydraulically jiggling the concentrate and the mobile mass at the screen, and a preliminary separator superposed above the pan discharge and into which the feeding means 55 discharges pulp, the rim of the separator being adjustable relative to the surface of the pan to form an annular mouth, through which a counter-current, derived from the jiggling means, runs outward, and means for adding clear water below the separator to the pulp and for varying the strength of the counter-current.

50 2. The combination in a concentrator, of a concave pan with a central discharge, means for feeding pulp at the center of the pan, a screen in the pan discharge and supporting 55 a mobile mass, the particles of which are too

large to pass through the screen, means for gyrating the pan to agitate said mass and the ore solids concentrated, the concentrate gravitating toward and through the screen and the gangue being washed outwardly by 70 the wave action and water flow, means for hydraulically jiggling the concentrate and the mobile mass at the screen, a preliminary separator superposed above the pan discharge and into which the feeding means 75 discharges pulp, the rim of the separator being adjustable relative to the surface of the pan to form an annular mouth, through which a counter-current, derived from the jiggling means, runs outward, and means for 80 adding clear water below the separator to the pulp.

3. The combination in a concentrator, of a concave pan with a central discharge, means for feeding pulp at the center of the pan, a screen in the pan discharge and supporting a mobile mass, the particles of which are too 85 large to pass through the screen, means for gyrating the pan to agitate said mass and the ore solids concentrated, the concentrate 90 gravitating toward and through the screen and the gangue being washed outwardly by the wave action and water flow, means for hydraulically jiggling the concentrate and the mobile mass at the screen, a preliminary 95 separator superposed above the pan discharge and into which the feeding means discharges pulp, the rim of the separator being adjustable relative to the surface of the pan to form an annular mouth, through which a counter-current, derived from the jiggling means, runs outward, and means for adding clear water below the separator to the pulp and for varying the strength of the counter-current.

4. In a concentrator, a pan, a bowl thereabove and spaced therefrom, said pan having a central discharge in its bottom, means to feed fluid up through said discharge to allow same to radiate through said space, 100 and means independent of the first named means and arranged in the space between the pan and bowl to direct fluid toward the bowl periphery.

5. In a concentrator, a pan, a bowl thereabove and spaced therefrom, means to vertically adjustably vary the space between the pan and bowl so as to allow variable restriction of the peripheral discharge between the pan and bowl, and means to feed water in said space from the center radially and outwardly therefrom.

6. In a concentrator, a pan, having a central foraminous discharge, a bowl above the pan spaced therefrom so as to form a restricted discharge in conjunction with the pan, at the bowl periphery, and having a central foraminous discharge, and means to feed fluid to said central discharge of the pan to allow the fluid to radiate from the 125 130

pan discharge and to pass through said discharge formed between the pan and bowl.

7. In a concentrator, a pan, a bowl overlying the pan in spaced relation thereto so as to form a restricted peripheral discharge, said pan and bowl having communicating discharges, and means to feed fluid up through the pan discharge into the space between the pan and bowl so that the fluid 10 may egress through said peripheral discharge.

8. In a concentrator, a pan, a bowl overlying the pan in spaced relation thereto so as to form a restricted peripheral discharge, 15 said pan and bowl having communicating discharges, means to feed fluid up through the pan discharge into the space between the pan and bowl so that the fluid may egress through said peripheral discharge, and 20 means disposed in the space between the pan and bowl for discharging fluid downwardly onto the pan adjacent said peripheral discharge.

9. In a concentrator, a pan and an ele-

ment coöperating therewith to form a substantially circular and horizontal chamber having a restricted peripheral discharge, a central concentrates discharge means in the pan, and means to feed water up through the central discharge into said chamber and 25 out of the peripheral discharge thereof.

10. In a concentrator, a pan and an element coöperating therewith to form a substantially circular and horizontal chamber having a restricted peripheral discharge, a 30 central concentrates discharge means in the pan, means to feed water to the center of the chamber and other means arranged in surrounding relation to the first named means to feed water adjacent to the peripheral discharge of the chamber.

In testimony whereof I have hereunto set my hand in the presence of two subscribing witnesses.
